US00D894180S

(12) **United States Design Patent** (10) **Patent No.:** **US D894,180 S**
(45) **Date of Patent:** **** Aug. 25, 2020**

(54) **SOLID STATE DRIVE**

(71) Applicant: **Shenzhen Longsys Electronics Co., Ltd.**, Shenzhen (CN)

(72) Inventors: **Li-Qing Yang**, Shenzhen (CN); **Xiao-Qiang Li**, Shenzhen (CN)

(73) Assignee: **Shenzhen Longsys Electronics Co., Ltd.**, Shenzhen (CN)

(**) Term: **15 Years**

(21) Appl. No.: **29/678,074**

(22) Filed: **Jan. 25, 2019**

(30) **Foreign Application Priority Data**

Jan. 3, 2019 (CN) 2019 3 0002629

(51) **LOC (12) Cl.** **14-02**

(52) **U.S. Cl.**

USPC **D14/348**

(58) **Field of Classification Search**

USPC D14/300-301, 348, 355-356, 363, D14/357-358; 361/679.31;

206/706-709; D9/424-430, 432-432;

D10/40, 70; D3/315-316; D13/103, 107

CPC H05K 5/03; H05K 1/144; H01L 21/00;

H01R 33/92; H01R 13/111; H01R 13/057

See application file for complete search history.

(57) **CLAIM**

The ornamental design for a solid state drive, as shown and described.

DESCRIPTION

FIG. 1 is a first perspective view of a solid state drive, showing my design.

FIG. 2 is a second perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines illustrate portions of the solid state drive and form no part of the claimed design.

1 Claim, 8 Drawing Sheets
